US0D1085847S

(12) **United States Design Patent** (10) **Patent No.:** **US D1,085,847 S**
(45) **Date of Patent:** **** Jul. 29, 2025**

(54) **FASTENING DEVICE FOR FURNITURE**
(71) Applicant: **Välinge Innovation AB**, Viken (SE)

(72) Inventor: **Johan Svensson**, Kattarp (SE)

(73) Assignee: **Välinge Innovation AB**, Viken (SE)

(**) Term: **15 Years**

(21) Appl. No.: **35/519,345**

(22) Filed: **Nov. 15, 2023**

(80) **Hague Agreement Data**

Int. Filing Date: **Nov. 15, 2023**

Int. Reg. No.: **DM/233547**

Int. Reg. Date: **Nov. 15, 2023**

Int. Reg. Pub. Date: **Dec. 15, 2023**

(30) **Foreign Application Priority Data**
